UNITED STATES PATENT OFFICE.

HENRY B. TOURTELLOT, OF QUINCY, MASSACHUSETTS, ASSIGNOR TO AMERICAN CAN COMPANY, OF NEW YORK, N. Y., A CORPORATION OF NEW JERSEY.

DISPLAY-RECEPTACLE.

1,247,036.

Specification of Letters Patent. Patented Nov. 20, 1917.

Original application filed February 3, 1913, Serial No. 745,842. Divided and this application filed August 24, 1914. Serial No. 858,198.

To all whom it may concern:

Be it known that I, HENRY B. TOURTELLOT, a citizen of the United States, residing in Quincy, in the county of Norfolk and 5 State of Massachusetts, have invented a new and useful Improvement in Display-Receptacles, of which the following is a specification.

This invention relates to an improvement 10 in display receptacles generally, and more particularly to improvement in display receptacles such as humidors for cigars and the like, and the present invention is a division of my application Serial No. 745,842, 15 filed Feb. 3, 1913, for cigar display humidors.

The invention consists in the novel devices and combination of parts and devices hereinafter described and claimed, and although 20 the embodiment of the invention shown on the drawing forming a part of this application and described in detail discloses a humidor, it will be understood that the invention has other applications and uses.

25 In the accompanying drawing which forms a part of this specification, Figure 1 is a longitudinal section of the improved humidor, the same being shown closed and standing flat. Fig. 2 is a cross sectional elevation, showing the humidor erected into the display position. Fig. 3 is a bottom or plan view, upon a somewhat similar scale, of the humidor as shown in Fig. 1.

A purpose of the herein described embodiment of the invention is to provide a 35 humidor of suitable size to receive a cigar box and its contents of cigars, such humidor also to contain the necessary moistening pads; to be furnished with the glass 40 hinged lid to close the same for the retention of the moisture; and to be furnished with a means for tilting and sustaining the humidor in display position, and for holding advertising matter.

45 In the drawing, A is a sheet metal wood or fiber box, the bottom B of which is flanged with a flange b interfolded with the sides of the box, and thus forming at the bottom a countersunk portion B¹, which 50 serves to strengthen the structure and at the same time to receive and contain a folded display stand consisting of the loop member or frame C, pivoted at c to the bottom of the box, and pivoted at c¹ to the swing-

ing plate D formed with a hook or offset d 55 into which hook, as shown in Fig. 2, the edge of the inclined box may be placed and securely held in the display position against movement in either direction. If, for any purpose, it is desired that the humidor shall 60 stand flat, the display stand is folded up upon itself and will then be contained, as indicated in Fig. 1, entirely within the countersunk bottom. The upper edge of the humidor box is all around formed with an 65 inwardly and downwardly extended flange a which serves to stiffen and strengthen the structure, and also as a holding place or receptacle for the necessary humidor pads. The humidor pads are preferably 70 made of perforated metal and blotting paper, the latter E held between two sheets of the former F, and stiffened at the edges by inturned flanges f. The perforated metal should preferably be coated with 75 waterproofing enamel or varnish to guard against rusting. When these moistening pads have been soaked with water, they can be placed in the humidor and removably 80 held therein by tilting them in the position shown in dotted lines in Fig. 1, and then pushing them into the vertical position, when the inward and downward turned flange a at the top of the humidor box will 85 serve to retain the pads in the vertical position against displacement. These pads may be placed one at each end or, in addition thereto, at the long sides of the box, as desired, the downwardly and inturned flange a serving as a holding means in either position.

When the humidor is in the display position supported upon the display stand, the upwardly extending leaf D¹ of this stand serves as a rest, upon which may be supported the hinged glass cover G, as indicated in dotted lines in Fig. 2, so that the humidor may be easily kept open when desired. The upwardly extending leaf D¹ and the support also offers a convenient place 95 to hold a price card or other advertising card, or, if desired, the top of the wooden cigar box, removed from said box, may be placed therein.

I claim:

1. An article of manufacture comprising a container having a body and a cover therefor, the body having an upwardly recessed

bottom, and a two-part hinged collapsible stand adapted to nest within said recessed bottom when it is collapsed, one of the two stand-parts being hinged at one of its ends 5 to the container, and the other stand-part being hinged to the free end of the first stand-part and being foldable to extend toward the hinge of said first stand-part, to lie within said recessed bottom of the container.

10 2. An article of manufacture comprising a container having a body and a cover therefor, the body having a countersunk bottom, and a two-part hinged, collapsible stand, the stand when collapsed adapted to be nested 15 within the countersunk bottom of the body, one of the stand parts being hinged at its front end to the container and at its rear end to the other stand part, the latter part having means to engage the rear end of the 20 container and having a cover supporting extension which also nests within said countersunk bottom.

3. A container of the character described comprising a body member having a pivoted cover, said body member having a 25 countersunk bottom and a stand for supporting said container in an inclined position, said stand including a loop member

pivotaly connected to the body and a plate pivotaly connected to the loop, the plate 30 having an offset with which the edge of the body engages, the plate and loop being so proportioned as to nest within the countersunk bottom of the body when the stand is collapsed, substantially as specified. 35

4. An article of manufacture comprising a container having a body and a cover therefor, the body having a countersunk bottom, and a two-part hinged, collapsible stand, 40 said stand including a loop member pivotaly connected to the container body, and a plate pivotaly connected to and foldable within the loop, the plate having an offset with which the edge of the body engages to support the body in an inclined position, the 45 plate and loop being adapted to nest within the countersunk bottom of the body when the stand is collapsed, substantially as specified.

Signed this 6th day of August, 1914, in 50 the presence of two witnesses.

HENRY B. TOURTELLOT.
